CLAIM

The ornamental design for an installment tool for electric connectors, as shown and described.

DESCRIPTION

FIG. 1 is a perspective view of an installation tool for electric connectors showing the new design.

FIG. 2 is a top plan view thereof.

FIG. 3 is a front elevation view thereof.

FIG. 4 is a bottom plan view thereof.

FIG. 5 is a left side elevation view thereof, shown at an enlarged scale; and,

FIG. 6 is a right side end view thereof.
